United States Patent Office.

HENRY A. RATTERMANN, OF CINCINNATI, OHIO.

Letters Patent No. 104,062, dated June 7, 1870.

IMPROVED MACHINE FOR PITCHING LAGER-BEER AND OTHER CASKS.

The Schedule referred to in these Letters Patent and making part of the same.

I, HENRY A. RATTERMANN, of the city of Cincinnati, county of Hamilton and State of Ohio, have invented a certain Machine to aid in the process of Pitching Lager-beer Casks, Barrels, or other Vessels, and for washing and rinsing the same, of which the following is a specification.

Nature and Object of the Invention.

The first part of my invention relates to the combination of certain wheels, in such a manner that a cask, barrel, or other vessel suspended in the main wheel, as hereinafter described, may be turned in a double rotary motion, which brings every part of the same to a certain point, so that, by the law of gravitation, an introduced fluid, (heated pitch, glue, varnish, or any other article,) must flow over every part of the inner surface of the same.

The object of this part of my invention is to do away with the manual labor of rolling, shaking, and turning over the ends of the cask, barrel, or other vessel, and to perform this work with greater accuracy and precision than by hand.

The second part of my invention relates to the process of cooling down the heated cask or vessel by mode of inserting an air-funnel into the bung-hole of the same, which, when the machine is in motion, will catch up the air and force the same into the vessel. By opening the faucet-hole at pleasure, a circulation of the air inside the vessel is effected, by which the same may be cooled down as rapidly as desirable.

The object of this part of my invention is to complete the pitching or gluing of the cask, barrel, or other vessel in a shorter time than now required, where the same must cool down through the walls or sides of the vessel.

The pitch, by cooling from the inside, also gets a more smooth and glossy surface than by the old mode of cooling.

The third part of my invention relates to the washing and rinsing of the cask, barrel, or other vessel.

By mode of various pulleys a fast or slow motion may be given the machine. A speed may be attained by which, if the cask, barrel, or vessel is partly filled with water, the same may be effectually washed or rinsed.

Description of the Accompanying Drawing.

Figure 1 is a front view of a machine embodying my invention, together with a section of a barrel.

Figure 2 is a side view of the same.

Figures 3 and 4 are drawings of extra arms, which may be inserted into the machine to make the same adaptable to smaller-size barrels or vessels.

Figure 5 is a drawing of the air-funnel.

General Description.

A is the main wheel, which suspends the cask, bar-

rel, or vessel X, which is hung on the pivot of shaft H, attached to cog-wheel C on the one end, and on the pivot of screw G on the other end.

On the headings or ends of the barrel or cask are first firmly screwed, or otherwise fastened, the iron plates I and K, the first of which has a round pivot-hole, and the latter a square pivot-hole.

The main wheel A rests with its shoulders upon, and is held in its vertical position by the rollers E, which are grooved out to pass the cogs of the wheel within the groove.

D is the spur-wheel, which, by the aid of a belt on the pulley F, and through the transmission therefrom by shaft N, turns the wheel A on the rollers, and, consequently, the cask, barrel, or vessel with it.

The cog-wheel C is, at the same time, forced to run in the cogs of the crown-wheel B, which is permanently fastened to the frame M, and thereby forces the cask, barrel, or vessel to rotate at the same time around its own axle.

One or more arms, L, are fastened, as required, into the wheel A, to make the same adaptable for smaller or larger-size vessels.

O is the air-funnel, which is inserted into the bung-hole of the cask, barrel, or vessel, in such a position that, if the machine is set in motion, the same will catch up the air and force the same into the cask, barrel, or vessel.

A double or triple pulley, F, is attached to the spur-wheel, so that a fast or slow motion may be given the machine at pleasure.

The cog-wheel C and the crown-wheel B have a bevel gearing.

Claims.

I claim as my invention—

The double rotary motion, as adapted to the use of this machine.

Also, the combination of the wheels A, B, C, and D, the shafts G and H, and the rollers E, to effect this motion.

Also, the arms L, for the purpose of making the machine adaptable to all sizes of casks, barrels, or vessels.

Also, the plates I and K, either fastened to the vessel or attached to the shafts G and H.

Also, the adaptation of a double or triple pulley, for the purpose of regulating the speed of the machine.

Also, the air-funnel O, and, conclusively, the frame M, all, of which is claimed substantially as and for the purpose hereinbefore set forth.

H. A. RATTERMANN.
